UNITED STATES PATENT OFFICE.

SIMEON LATHAM GOULD, OF GARDINER, MAINE, ASSIGNOR OF ONE-HALF
TO WILLIAM A. RUSSELL, OF LAWRENCE, MASSACHUSETTS.

PAPER-PULP-FINISHING ENGINE.

SPECIFICATION forming part of Letters Patent No. 337,489, dated March 9, 1886.

Application filed November 12, 1885. Serial No. 182,526. (No model.)

To all whom it may concern:

Be it known that I, SIMEON LATHAM GOULD, a citizen of the United States, residing at Gardiner, in the county of Kennebec and State of Maine, have invented certain new and useful Improvements in Paper-Pulp-Finishing Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to "paper-pulp engines," and belongs especially to that class termed "finishing-engines," since they receive the ground rags or other fibrous material from the beating-engines and reduce it more thoroughly and evenly, and thereby render the entire mass of more uniform consistency preparatory to its being run into the stuff-chest, whence it is delivered upon or to the paper-making machine.

25 In this particular class of engines rapidity of feed is of the utmost importance; hence there should be a very large area of beating-surface combined with means for easily discharging the pulpy mass passing through.

30 My invention contains several important features, prominent among them being primarily the method of feeding the engine centrally, or thereabout, and discharging the beaten stock peripherally of the same. Thus 35 the centrifugal force is rendered an active agent in accelerating the free flow of the material through the machine, and there are no counter-currents to oppose the discharge.

Secondly. In the arrangement of the rotary 40 grinding-disk, by which the feed is permitted to enter upon both sides, in order to obviate the end thrusts or shrugs arising from having the feed enter only upon one side; hence I am enabled to balance the grinding-disk. Hitherto this end-thrust has been a very serious 45 objection, and various expedients have been adopted to construct a suitable device to receive and overcome this endwise movement of the rotary shaft carrying the grinding-disk.

50 Thirdly. In the peculiar construction of said disk and in the general arrangement and dis-

position of the various operative parts, which will be more fully hereinafter explained.

The drawings accompanying this specification represent, in Figure 1, a vertical central 55 longitudinal section of a paper-pulp-finishing engine embodying my improvements, while Fig. 2 is an end view, and Fig. 3 a plan, of the same. Fig. 4 is a section of a portion of the grinding-disk transversely of the cutting-bars, 60 taken on line *xx* of Fig. 5, while Fig. 5 is a top view, and Fig. 6 an enlarged cross-section, of the roll and shaft.

In the drawings, A represents a rectangular frame resting upon suitable standards, *a a'*. This frame supports a rotary shaft, B, upon which is secured a grinding-plate or circular disk, C, the latter being provided on both sides with a series of cutting bars or knives, *b b*, &c., radially disposed thereof. 70 These bars are adapted to engage and co-operate with opposite but similarly-disposed bars *c c' c'*, secured within two circular stationary disks or bed-plates, D D'. These last are, moreover, securely bolted to the end 75 heads, E E', adjustable endwise upon the shaft B, and are adapted to enter and closely fit the central circular shell, F, the whole forming a tight hollow casing, G, within and through which the ground material is entered and discharged.

It will be seen that the supply or inlet passages *d d'* connect with a settling-box, *e*, the latter being employed to receive and retain any small pieces of iron-scrap which may have 85 come from the beating-engines. Moreover, it will be noticed that these passages deliver their contents centrally or thereabout of the rotary disk C, whence it is discharged through an outlet, I, common to both sides of the grinding-disk, or to the spaces existing between the 90 said disk and its co-operating bed-plates.

The construction of the latter parts D D' is the same usually employed—that is, they are composed of a series of steel bars radially disposed, which are retained in position by the usual wood filling. For convenience of repairs I have bolted them to end heads and adapted the latter to enter the central shell, F, tightly, but still capable of adjustment 95 therewith. This movement of the end heads, E E', containing the bed-plates, is to provide 100

means by which to regulate the space between the latter and the rotary grinding-disk revolving between them. Thus the operator is enabled to reduce the stock passing through the engine more or less, as is desired. This adjustment is effected by means of levers $H H'$, pivoted at one end to the standards $a a'$, while their opposite extremities are actuated by hand-screws $f f'$, moving upon a screw-threaded rod, g , suitably mounted upon the frame A. To maintain said heads in any fixed relative position with respect to the grinding-disk, these levers $H H'$ are furthermore pivotally attached to the hubs or extensions $h h'$, exteriorly formed upon the adjustable heads $E E'$. Thus it will be understood that advance of the hand-screws $f f'$ toward each other will cause the end heads, $E E'$, and their bed-plates $D D'$ to approach the grinding-disk, and thus diminish the space existing between the latter and the bed-plates and cause the stock to be reduced more finely, while the reverse movements of said screws produce an opposite effect.

The peculiar construction of the rotary grinding-disk requires special description, and upon reference to Figs. 4 and 5, it will be seen that the bars $b b$ are arranged radially of the shaft. Moreover, their dimensions in width is equal to the width of the disk considered as an entirety, while their lower ends are provided with oppositely-disposed rectangular notches $i i'$. In the making up of this disk or grinding plate upon its driving-shaft, I first provide a hub, j , formed with an annular rib, k , and with a sleeve, l , of a bore sufficient to admit the driving-shaft B. The bars are now placed in position with their inner ends resting upon this sleeve, when the opposite corresponding hub, j' , is slipped over the sleeve l , the rib k' engaging in the slots i' , when the clamping-nut m is turned home and the knives are in position. Wood filling $n n$, &c., is now driven in, and lastly, to prevent the thrusts and shocks incidental to the working of the engine from loosening and displacing such filling, an iron band, o , is shrunk upon the circumference of the now completed disk C.

The operation of the machine and the course and flow of the stock therethrough is as follows: The pulp discharged into the settling-vat e is there freed from any hard metallic substance liable to injure or damage the rotary disk, whence it is conducted through the pipes $d d'$ and entered centrally but simultaneously upon opposite sides of the grinding disk. The latter, being in rapid rotation, at once seizes and conveys the stock quickly to its circumference, while in its passage it is subjected to innumerable shearing blows or cuts from the grinding-bars, and thus emerges in a finely-commminuted state and passes into the discharge-pipe F.

It will be readily understood how great are the advantages by making both sides of the grinding-disk equally active and efficient, and this can be accomplished only by feeding at

the center and discharging at the periphery of the revolving disk. Furthermore, by this system it will be seen that the thrusts consequent upon the grinding or work accomplished on one side are balanced or counteracted by the work upon the opposite but corresponding face of the rotary disk, and hence no "step" is required, which instrumentality has been hitherto such a serious objection in engines of this description.

A second and great advantage is that the stock is advanced by the centrifugal force, and hence is always impelled with and not against it; hence there are no counter or opposing agencies or currents, and the flow of the material is being expedited continually the more rapidly the engine is driven.

I am well aware that engines of this class have been constructed—such as the well-known Kinsland engine—in which a rotary grinding-disk laterally armed with knife-bars has been employed in connection with two oppositely-disposed stationary bed-plates; but in this machine the inlet and discharge feed-pipes were both centrally disposed; hence the back or discharge side of the engine was practically inoperative, since the pulp was being forced against the centrifugal tendency to retard and maintain it upon the circumference of the rotary disk. So, it was found that the feed was very sluggish, and the stock had to be forced through under pressure, while the work on the front side was greater and the pressure greater than upon the rear side; hence uneven wear and a step was required.

I do not desire to be limited to the precise form and construction of parts constituting the engine as herein shown, since various alternative devices may be substituted therefor without departing from the spirit of my invention—as, for instance, in lieu of adjusting the bed-plates with the screw-threaded rod and the levers, as shown, a rack and pinion may be employed with equally good results.

I claim—

1. A pulp-finishing engine, constructed substantially as described, in which the material to be ground is entered centrally upon each side of the grinding-disk and discharged at the circumference of the latter.

2. In a pulp-finishing engine, the combination, with a circular grinding-disk furnished with cutting-bars on each face, of the stationary but adjustable bed-plates co-operating therewith, and the inlet-supply pipes which enter centrally upon each side of said disk, substantially as and for purposes set forth.

3. The method herein described for feeding paper-pulp engines of the class mentioned, whereby the stock is admitted centrally upon each side of the rotary disk, to eliminate the end-thrusts and balance said disk, and thence discharged at the circumference by and in unison with the centrifugal force incident to the rotations of said grinding-disk, substantially as described.

4. In combination with the fixed shell F, con-

taining a rotary grinding-disk, the stationary bed-plates D D', secured within the end heads, E E', and the latter adjustable with respect to said shell and its disk C, whereby the space 5 between the co-operating bed-plates and the armed disk is regulated to suit the material passing through.

5. The combination, with the fixed shell F and the adjustable end heads, E E', of the actuating-levers H H', and operative mechanism, 10 by which the space on either side of the rotary disk is regulated, substantially as herein set forth.

6. A circular grinding-disk composed of a series of knives radially disposed and of a 15 width equal to the thickness of the disk to which they are secured, whereby the opposite edges of each bar shall constitute an active cutting-surface, substantially as stated.

In testimony whereof I affix my signature in 20 presence of two witnesses.
